UNITED STATES PATENT OFFICE.

WILLIAM FREDERICK MOODY, OF ROMSEY, ENGLAND.

SIGNPOST.

Application filed May 25, 1925. Serial No. 32,774.

To all whom it may concern:

Be it known that I, WILLIAM FREDERICK Moody, a subject of the King of England, and resident of Romsey, in the county of 5 Hampshire, in the Kingdom of England, have invented new and useful Improvements in Signposts, of which the following is a specification.

This invention relates to sign-posts and 10 consists of a tubular standard with adjustable fittings to which sign-plates are attached spirally in step pattern so arranged to admit clear vision between the standard tube and the sign and thus permit of observing 15 the direction at a glance, so as to avoid delay of traffic and accidents. An important feature is, that colours are adopted for the signs which make them equally effective for town, country, coast, or railway 20 use, the present mode of direction having become too varied and numerous to be effected.

I will now describe the drawings,

Figure 1 illustrates a standard or sign-post fitted with a light and suitable for town and general use. Fig. 2 shows a section of the sign post to larger scale; Fig. 3 shows hinged cup flanges for carrying arms; Fig. 4 shows these cup flanges in open position; Fig. 5 shows the base casting enlarged; Fig. 6 shows a plan of the flange in Fig. 3; Fig. 7 shows a front of a sign plate; Figs. 8 and 9 show diagrammatically the position of the top and lower signs illustrated at Fig. 1.

In these drawings the standard B is designed to give clear view so as not to screen any part of the sign. It consists of a length of steel tubing inserted and fixed by two collars into a conical shaped casting A which 35 has central lugged sockets top and bottom; the casting A also has claw fittings at its base for fixing into the soil or bolting to some firm surface. To the standard B is attached a pair of cup flanges C coupled 40 and fixed in suitable manner and adapted to be slid on B. Around the rim of these flanges are holes C¹ into which fit the arms D. These arms comprise a suitable length of small steel tubing to which is slantingly secured another short length D¹ and a horizontal member D² forming triangle like fittings. In Fig. 1 the width apparently varies 45 in consequence of the drawing being given in slight perspective. An extension D³ of tube D² for fixed position signplates may be provided. Thus the arms D can swing hinge 50

55 fashion till fixed by the expansion rod E which goes through the tube D and locks it in required position as shown in Figs. 2 and 3. The open triangle of the arms D allows clear vision between the standard tube B and the signplates G. Six or more signplates may be placed on each arm or a large single plate cut to pattern of the whole where several places lead from the one direction 60 only, but only two arms should be on the same level, extra flanges being used two above each other according to the number of different roads, said extra arms being in the form of triangles K of small tubes secured or welded together. By this means 65 a dozen to twenty or more different names can be clearly seen at some distance. The signplates G are made of sheet metal. The sign disposed above the arm D is for streets 70 only; it should be rather smaller than the others and have entire white background with red lettering. The under signs are for 75 places and distances, with the same colour 80 background and black lettering. The sign L bearing the name of the town or village is attached vertically by screws in the name-plate to the standard tubing B showing the name from either way and has for its background yellow with blue lettering. 85

90 For illuminating by gas or electricity suitable piping or coil is simply inserted through the standard tube into the top fitting and may be carried over the arms if desired to light each separately. Where no lighting is required the top of the standard tube is fitted with a circular metal plate F enamelled white with a red star in the center and having a ferruled cap attached at the bottom which fits on the standard tube. 95

100 Fig. 1 illustrates a suitable standard for squares or open spaces where half a dozen or more roads join each other. On the standard are shown ten places, four streets and name of town below with only two arms on the same level. A similar standard of less height with the necessary fittings is suitable for country roads. Where there are a number of roads or cross-roads extra flanges, arms and signplates, are used as required for the names of places. Each arm D covers a quarter circumference and the signplates are placed thereon spirally in step-down pattern the angles of the signplates varying to the road they direct. This 105 spiral step formation of the signplates is important for clear vision. Where an ex-

cessive number of roads lead from either quarterly direction it is preferable to mount another flange and arm instead of placing five or six signs on one arm. The easy adaptability of fixing the signplates is also of much advantage for exchanging the names or increasing them as desired. The ten inch depth fixed signplates are concave horizontally through the center and have strap attachment. Where signs are needed under each other for two or more places in the same direction they may be held by means of an S hook, the position for this being near the indicator end. The hook is made of thin flat steel, the edges rounded, and carrying small screws for attachment to plates. The arc shaped vertical signplate is secured to the standard tube by means of small countersunk screws in the nameplates. For directions leading off the main road the italic lettering is used. Numerals on this type of spiral step direction will hardly be found necessary. In narrow parts where it is desired to use the standard with only one or two arms, each arm may cover half circumference provided the arms are made with sufficient step axle fitting for the step arrangement of the signplates.

Diagram H shows the setting for the upper signs of Fig. 1, and diagram H¹ those on the lower arms. The signplates should be alternately arranged on every other axle fitting to admit clearest possible vision to those at rear angles. The light from globe F where this is illuminated is thus shed evenly on all the signs on the post.

I claim:

1. An improved signpost comprising ad-

justable standards, slidable, cup-like flanges secured thereto, triangular fittings mounted on the flanges, signs mounted on the triangular fittings in spiral stepwise formation in relation to the standard, as described.

2. An improved signpost, comprising adjustable standards, slidable, cup-like flanges secured thereto, triangular fittings mounted on the flanges, signs mounted on the triangular fittings in spiral stepwise formation in relation to the standard, and illuminating means for the signs, as described.

3. An improved signpost, comprising adjustable standards, slidable, cup-like flanges secured thereto, triangular fittings comprising tubes welded together and pivotally carried in said flanges, locking means for wedging the triangular fittings in position, additional triangular fittings secured to the first named triangles arranged to give clear vision of the signs mounted in spiral, stepwise formation in relation to the standard, as described.

4. An improved signpost, comprising adjustable standards, slidable, cup-like flanges secured thereto, triangular fittings comprising tubes welded together and pivotally carried in said flanges, locking means for wedging the triangular fittings in position, additional triangular fittings secured to the first named triangles arranged to give clear vision of the signs having bent over ends to clip on the triangular fittings, and wedges for holding same fast, such signs being mounted in spiral, stepwise formation in relation to the standard, as described.

WILLIAM FREDERICK MOODY.
